THOMAS M. WINDER AND WILLIAM R. MURROW, OF INDEPENDENCE, KANSAS.

OIL-WELL TORPEDO.

Application filed May 16, 1927. Serial No. 191,588.

Our invention relates to certain improvements in a torpedo for shooting oil wells of the type disclosed in an application of Mark D. Mitchell, Serial No. 659,321, filed August 5 25, 1923. The torpedo of said application consists of a shell of generally cylindrical shape, the lower end of which is charged with a small amount of explosive above which is mounted a cage or framework 10 adapted to receive a percussion cap for detonating the high explosive, a spring pressed hammer being mounted on the cage and adapted to be cocked and released after a predetermined time to explode the percussion cap. In said torpedo of the Mitchell 15 application the hammer was held cocked by a screw trigger which, after the hammer had been retracted, was screwed down to a position in which it engaged the free end of the 20 hammer. The head of the screw trigger was bifurcated or slotted to receive the finger piece of the alarm-winding key of an alarm clock inserted into the casing face side up above the screw trigger. The alarm clock, 25 which, as disclosed in said application of Mitchell was of the usual cylindrical type, was to be wound and set so that after a predetermined time the alarm would go off revolving the winding key thereof and also revolving the screw trigger to release the 30 hammer. It is the object of the present invention to further insure against the premature setting off of the alarm and consequent detonating of the torpedo and with this in view 35 we provide a latch to engage the winding key of the alarm mechanism of the clock which latch is withdrawn from engagement with the alarm winding key prior to the time for which the clock has been set by the 40 engagement therewith of the winding key of the time mechanism of the clock. Thus the torpedo is protected from premature explosion not only by the mechanism of the clock by which the alarm is set off at the predetermined time but also by the latch controlled 45 by the timing mechanism of the clock.

In the drawings accompanying and forming a part of this specification:

Figure 1 is an axial section through such 50 a torpedo, parts being shown in elevation.

Fig. 2 is a transverse section through a portion of the clockwork mechanism.

Fig. 3 is a transverse section through the 55 torpedo on the plane of line 3—3 of Fig. 1.

Figs. 4 and 5 are isometric views of detail. We will first describe so much of the pres-

ent construction as is substantially disclosed in said Mitchell application and thereafter refer to the improvements thereon which constitute the present invention.

In the drawing the container 6 is shown as a metal shell of generally cylindrical form but tapered at the lower end. The casting is hollow and forms a chamber, the lower end of which is intended to contain a quantity of high explosive 7. The upper end of the casting may be bored out to form a shoulder 8 above the explosive containing end thereof, said shoulder forming a seat for a metal cage or framework 9 for the timing 70 and cap exploding mechanism.

The cage comprises a lower shelf or partition 10 and an upper shelf or partition 11, longitudinal members 12, 13 connecting said shelves and a seat or support for a clock 75 above the upper shelf. The support for the clock comprises a ring 14 of an external diameter to fit within the bore of the casing and legs 15, 16 supporting the seat 14 at a suitable distance above the shelf 11. By 80 reference more particularly to Fig. 1 it will be noted that the annular seat 14 is designed to receive a cylindrical alarm clock of a kind common upon the market and which has a rearwardly extending portion 17 of somewhat less diameter than the main body 18 of the clock. The main body of the clock is of such diameter as to loosely fit within the shell or container and rest upon the ring 14 and the portion 15 of the clock of less diameter enters within the ring. The lower part 85 of the shelf 10 is formed with a boss or projection 19 which is perforated vertically, the hole being counterbored as at 20 to receive a sleeve 21, and the upper end 22 of the hole is of smaller diameter to receive a firing pin 23. The bore of the sleeve 21 is 90 adapted to receive a cap of any known or preferred type and the cap when in position is adapted to be fired by pin 23.

Between the supports 13, of which there are two, is pivoted a hammer 24 and a spring 25, surrounding the pivot bar 26 of the hammer, which throws the latter against the firing pin when the hammer is released, as presently to be described. The free edge of the hammer is chamfered at 27 to afford a suitable bearing for the trigger screw 28 by which the hammer is temporarily held in cocked position when the device is set 100 for use. The trigger screw is threaded into a hole in shaft 11 and the head thereof is

slotted at 29 for a purpose which will presently appear. The trigger screw is so located that when the alarm clock is on the seat of the cage in the position as shown the finger piece 30 of the key of the alarm mechanism enters the slot 29 of the screw.

In Figs. 1 and 2 the usual setting stem for the time mechanism is shown at 31 and the setting stem for the alarm mechanism at 32, 10 the winding key for the time mechanism being shown at 33.

The operation of the mechanism thus far described will be apparent. In preparing the torpedo for use the lower end of the 15 chamber is partially filled with high explosive, a cap placed in the tube 21, the firing pin 22 put in position, the hammer retracted against the pressure of its spring and the trigger screw screwed down until 20 its conical end engages the face 27 of the hammer to hold it in retracted position. The cage with its associated parts is then placed in position as shown in Fig. 1, resting upon the shoulder 8. The clock is wound 25 both as to the time mechanism and the alarm mechanism, these two mechanisms are set in the usual way so that the alarm may be released at a predetermined time and the clock is placed on its seat. The alarm key 30 is, of course, revolved when the alarm is released, and revolving the screw 28 to withdraw the latter, releases the hammer which strikes the firing pin and fires the cap.

Coming now to the invention which forms 35 the subject matter of the present specification, the purpose thereof is to lock the alarm key so that it may not be accidentally revolved to permit the device to be fired until after a predetermined time such as that required 40 after the setting and assembling of the device to lower the same into position in the well. With this in view we equip the clock with a sliding latch 40 which may be set to engage the key 30 of the alarm mechanism 45 and withdraw therefrom by the winding key 33 of the timing mechanism of the clock. In the form of the invention shown, the stem of key 30 is perforated as at 41 and the latch 40 mounted so as to have a limited 50 sliding movement to permit its end 42 to be engaged in the hole 41 or withdrawn therefrom. In the preferred construction shown the latch is bifurcated to surround or embrace the time setting stem 31 and the 55 stem of the time-winding key 33. These stems may be grooved to better serve as guides for the latch, though this is not essential an eye or loop 43 guides the end 42 of the latch. Just beyond the winding 60 key 33 the latch is provided with a blade 44 so located upon the latch that when the end of the latter is in engagement with the hole in the winding key of the alarm mechanism the blade is close to the winding key 65 of the time mechanism. The location of the

blade 44 on the latch is such that as the cross piece 45 of the time mechanism winding key revolves, the latter engages said blade and so acts to withdraw the latch from engagement with the key 30 of the 70 alarm mechanism.

In preparing the apparatus for operation the clock, before being dropped onto its seat is wound and set as above described, the winding key 30 being left in such position 75 that the latch may enter the hole therein and the winding key 33 for the time mechanism being left in the position shown in dotted lines in Fig. 2 so that the blade 44 may come close to the stem 33 as shown in 80 Fig. 2.

After the latch has been set as indicated in Fig. 2, and the clock dropped onto the seat, the operation of the timing mechanism of the clock slowly revolves the cross bar 85 45 of the time-winding key so that the latter slowly withdraws the latch into inoperative position. Enough time elapses in this operation to permit the closing of the bomb or torpedo and its lowering into the well. 90 After the latch is withdrawn, the continued movement of the clock ultimately results in setting off the alarm mechanism as above described.

The upper end of the torpedo is closed by 95 a screw plug 50, a washer 51, serving to prevent the entrance of water or oil to the interior of the torpedo when the latter is lowered into the well to be shot.

It will be understood that in shooting a 100 well the shattering charge is first introduced as usual and then the torpedo lowered onto the shattering charge and the tubing and tackle withdrawn out of the danger zone. The torpedo having properly been set it 105 explodes after the predetermined interval and sets off the shattered charge.

We claim:

1. A clockwork mechanism for the purpose described, having a timing and an alarm 110 mechanism, including a winding key for each, and a latch movable into and out of engagement with the alarm key and engaged by the key of the timing mechanism to withdraw it from engagement with the alarm 115 key.

2. A clockwork mechanism for the purpose described, having a timing and an alarm 120 mechanism including a winding key for each and a latch mounted to slide into and out of engagement with the alarm key, said latch having an abutment in the path of the cross bar of the key of the timing mechanism whereby the rotation of the key of the timing mechanism withdraws the latch.

3. In a device of the class described, a hammer, a trigger element for holding the hammer in retracted position, time controlled means operating after a predetermined interval to move the trigger to release 125

- the hammer, a latch for holding the trigger against hammer releasing movement, and time controlled means for withdrawing the latch.
5. 4. In a device of the class described, a hammer, a screw-bolt for holding the hammer in retracted position having a head adapted to engage the alarm key of a clock, a latch adapted to engage the screw bolt 10 and prevent its turning and a support for an alarm clock adapted to hold a clock with its alarm key in engagement with said screw bolt and its time key in position to engage and withdraw the latch.
15. 5. In a device of the class described, a cage having a receptacle for a percussion
- cap, a hammer on the cage for exploding the cap, a rotary trigger for holding the hammer in retracted position and adapted to release the hammer when rotated, an 20 alarm clock seated on the cage with the alarm winding key thereof in rotating engagement with said rotary trigger, a latch movable into and out of engagement with said winding key and extending into the 25 path of rotation of the finger piece of the timing mechanism key of the clock, whereby the rotation of the latter withdraws the latch from engagement with the alarm winding key.

THOS. M. WINDER.
WILLIAM R. MURROW.
